CLAIM

The ornamental design for a compact disc case, as shown and described.

DESCRIPTION

FIG. 1 is a perspective view of a compact disc case showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front elevational view thereof, shown fully extended, the rear being unornamented; and

FIG. 9 is a perspective view thereof shown folded into a triangular position.
